[57] **CLAIM**

The ornamental design for a pillbox, substantially as shown and described.

DESCRIPTION

FIG. 1 is a top perspective view of a pillbox showing my new design, with one compartmented area in a partially open position;

FIG. 2 is a bottom perspective view; and

FIG. 3 is an end elevational view thereof.

The dash lines showing numerals are for illustrative purposes only.

FIG. 1

FIG. 2

FIG. 3
